UNITED STATES PATENT OFFICE.

HARRY BATES, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

1,427,345.

Specification of Letters Patent. Patented Aug. 29, 1922.

Application filed February 25, 1919. Serial No. 279,121.

To all whom it may concern:

Be it known that I, HARRY BATES, a citizen of the United States, residing in New York city, in the county of New York and 5 State of New York, have invented certain new and useful Improvements in Typewriting Machines, of which the following is a specification.

This invention relates to typewriting and 10 other similar machines producing written work, and is herein disclosed as applied to an Underwood typewriting machine.

In writing machines like the Underwood typewriting machine and others, which are 15 known as "visible writers", the typist has the great advantage of seeing the written work, but in offices where other people pass near the machine, the other people can make use of the fact that the writing is visible, with 20 the result that the writing which may be confidential or semi-confidential, is made public property. According to the present invention, the typewriting or other machine may be provided with a device which is 25 adapted to keep much, or substantially all, of the writing covered, thus enabling the typist to leave the machine with written matter in it, assured that the writing will remain covered, unless the covering device is 30 deliberately removed.

The device may advantageously take the form of a light flexible sheet, which is supported in front of the platen in such a manner that it stands clear of the printing ribbon and the swinging type-bars, and falls rearwardly over the printed sheet. The cover may be detachably mounted in a pair of clips which hold it just above the writing line, with the result that the last line or two 35 of writing is visible to the typist while seated at the machine, but invisible to anyone whose eyes are much above the level of the platen. The clips may be swingable upon the carriage, and normally caught down to the 40 above-described position, but adapted to be released by depression of a finger-piece, with the result that the cover is swung clear of the written matter. If desired, there may be provided two catching points, so that the 45 swinging cover may be caught at an intermediate point, so that a number of lines just written are in sight of the typist, but most 50

or all of the rest of the writing is concealed from the eyes of anyone standing up.

If the cover takes the form of a sheet of 55 light pressboard or heavy ledger-paper, the support for the clips may be very light, and may lie along the sides of the carriage, thus being out of the way, when the concealing sheet is detached, and adding only a negligible weight to the carriage.

The device is herein shown as attached to the carriage by screws threaded into the usual screw-holes for holding the cover-plates of the shift-frame in place, thus permitting any person of ordinary skill to attach it to existing machines.

Other features and advantages will hereinafter appear.

In the accompanying drawings,

Figure 1 is a fragmentary, perspective view of an Underwood typewriting machine, showing the invention as applied thereto, and as covering all but the line actually at the printing point.

Figure 2 is a detail, side view of a catch-release.

Figure 3 is a perspective of a second catch.

Figure 4 is a sectional, side view of the parts as shown in Figure 1, viewed from the 80 other side.

Figure 5 is a similar view with the second catch effective.

Figure 6 is a similar view with the concealing sheet carried clear of the work-sheet.

In the usual Underwood typewriting machine, the revolute platen 1 is fast to an axle 2, journaled in the ends 3 and 4 of a shift-frame 5, which is shiftable in the carriage 6. Whenever one of the usual character-keys (not shown), is depressed, it carries down its key-lever (not shown), to swing its type-bar 7 upwardly and rearwardly, causing its type 8 to print upon a work-sheet 9 at the front of the platen 1, 90 and curved around it. The type prints through a ribbon (not shown), in the usual ribbon-carrier (not shown), the ribbon being drawn from and wound upon spools (not shown), at each side of the machine. The 100 printing point is just at the upper edge of the usual wing-scales 10, and the platen 1 is rotated by the usual line-space-lever 11 to advance the work line after line to the print-

ing line. The work-sheet is usually held close to the platen and curved rearwardly over the top of it by paper-fingers 12, which include offset front extensions 13, carrying 5 front rolls 14, to extend over and bear upon the edges of the work-sheet, and which are slidable along a rear transverse rod 15, by which the fingers 12 are supported and around which they may be swung. Thus the 10 lines of writing upon the work-sheet lie above the wing-scales, and, when many are written, lie nearly horizontal across the carriage, as the work-sheet bends backward and sometimes lies upon the upper edge of the 15 usual paper-table 16.

To conceal these written lines, the structure here disclosed provides a concealing sheet 17, which is adapted to be clipped into a clip 18 near each end of the carriage.

20 While the concealing sheet 17 may be any suitable sheet, it is advantageously made of a sheet nearly as stiff as heavy ledger-paper, and rather dark in color to make it opaque and less likely to show dirt marks, 25 as from handling. It may bear any suitable printing, as advertising matter, or a legend of reproof to the onlooker, such as "Don't look at these private letters. This means you." The clips 18 are advantageously the 30 front ends or are mounted on the front ends 19 of rock arms 20, fast to a bail or rock shaft 21, adapted to revolve within the usual roll top 22 of the paper-table 16, and are so located that they will hold the concealing 35 sheet 17 just clear of the rolls 14 and one or two line-spaces above the wing-scales 10, thus permitting the typist to easily read the last line or two of writing while seated before the machine, although the writing is 40 wholly concealed from any one whose eyes are higher up. The clips 18 may be in the form of flat springs 23 fast to and lying against the front faces of the ends 19. The springs are advantageously extensions of 45 small plates 24, riveted to the backs of the arms 20, and the heads of the rivets on the front may serve as bosses to increase the grip of the springs on the concealing sheet.

The bail or shaft 21 may be journaled 50 on brackets held by screws 25, passing through the usual screw-holes in the top plates 26 at the end of the shift-frame, and may be under tension of a spring 27, coiled around it and fast to a collar 28 on it, and 55 tending to swing it against a bracket-stop 29 fast on the bracket 30, said latter stop forming an anchorage for the spring. The hubs 31, by which the arms are fast to the shaft of the bail, may form thrust bearings 60 for the ends of the shaft, and screws 32 threaded into the shaft may hold the short projecting ends of the shaft against slipping out of the brackets 30. If the bracket 30 is held in place by a single screw 25, it may 65 be held against turning by a lug 33 lying

within the shift-frame, and the screw may be identical with the usual screw which holds the cover-plate upon the shift-frame end, or only slightly longer.

To hold the covering-sheet against being 70 swung away from covering position by the spring 27, a latch 34 may automatically catch the arm down when drawn to covering position, said latch being in the form of a one-way catch pivoted at 35 upon the right-hand arm 20, and normally pressed into position by a spring 36 to catch under a lug 37 upon an extension 38 of the bracket 30. When the arm is depressed, a cam face 39 on the catch causes the lug to cam it rearwardly until below the lug 37, and then the spring 36 springs it to effective position. To limit the throw of the catch 34, it may include a slot 40 embracing a pin 41 fast on the arm. 80

To release the catch 34 to permit the spring 27 to carry the covering-sheet up, a finger-piece 42 may be pivoted at 43 upon a lug 44, depending from the extension 38, the finger-piece being in the form of a lever 90 and having a cam end 45 adapted to strike the cam face 39 of the catch when the finger-piece 42 is depressed, thereby carrying the catch 34 clear of the lug 37 and allowing the spring 27 to lift the covering-sheet. The 95 finger-piece may be normally drawn to ineffective position by a spring 46 to lie against an arresting lug 47 fast on the extension, and is arrested at the end of its throw by striking the under side of the lug. 100

If it is desired to set the covering-sheet to permit more than the one or two lines of writing to be visible to the typist, means may be provided to arrest the arm at a second position (Figure 5), slightly above the position described above. In the structure shown, this secondary arresting may be effected by a one-way catch slidable on the extension, and adapted to catch over a lug on the arm. This catch may be in the form of a slidable bolt 50 adapted to slide in the ears 51 of a small bracket 52 fast on the extension, and normally pressed by a spring 53 encircling the bolt, so as to intercept the lug 49. The bolt will not interfere with the 115 drawing down of the arm, since it is provided with a cam face 54 adapted to permit the lug 49 to cam it out of the way during the descent of the arm. The bolt has its throw limited by the boss 55 of the finger-piece 57 for handling it, and by a small lug 56 adapted to strike the ear in which it slides. 120

Since the Underwood typewriting machine, the ends of the platen stand well clear 125 of the ends of the shift-frame, there is ample room for the arms 20 to descend between the platen and the ends of the frame, and yet permit the arms 20 to clear the usual line-space-control-lever 58 and its finger-piece. 130

It will be noted that the ends 19 of the arms, on which the clips 18 are mounted, extend inwardly quite a distance parallel to the face of the platen, and that the downward throw 5 of the arms is arrested by the rod 15. The bracket 29 may arrest the arms 20 at such a point that the covering-sheet 17 falls behind the carriage, and thus is out of the way in adjusting work-sheets.

10 Variations may be resorted to within the scope of the invention, and portions of the improvements may be used without others.

Having thus described my invention, I claim:

15 1. In a front-strike typewriting machine, the combination with a traveling carriage and a revolute platen therein, of a flexible device adapted to screen the part of a work-sheet above the printing point on the platen, 20 and so positioned as to permit the typist seated at the machine to read the written line at the printing point, a mounting for said device pivoted at the rear of the carriage, a spring normally tending to swing 25 the device clear of the carriage on its mounting to ineffective position, and detaining means adapted to hold the device against said spring in either of two screening positions to permit the typist to have a more or 30 a less extended view of the written work-sheet.

2. In a front-strike typewriting machine, the combination with a traveling carriage and a revolute platen therein, of a shaft 35 journaled in said carriage, rock arms comprising clips fast to said shaft adapted to support a sheet to screen the part of a work-sheet above the printing line of the platen, a spring normally tending to swing said shaft 40 to raise said clips and swing the screening sheet to ineffective position, and detaining means to hold the shaft against the tension of the spring in either of two other positions to screen more or less of the work-sheet.

45 3. In a front-strike typewriting machine, the combination with a traveling carriage and a revolute platen therein, of a shaft journaled in said carriage, rock arms comprising clips fast to said shaft adapted to 50 support a sheet to screen the part of a work-sheet above the printing line of the platen, a spring normally tending to swing said shaft to raise said clips and swing the screening sheet to ineffective position, means 55 to hold the shaft against the tension of the spring in either of two other positions to screen more or less of the work-sheet, and devices whereby the shaft, when once released, is arrested at the second position.

60 4. In a front-strike typewriting machine, the combination with a traveling carriage and a revolute platen therein, of a shaft journaled at the rear of the carriage, a rock arm at each end of the platen fast upon 65 said shaft, a clip upon each arm adapted to

hold a screening sheet to conceal the lines written upon a work-sheet, a spring tending to swing said arms upwardly and rearwardly to carry the screening sheet to ineffective position behind the carriage, and a catch 70 adapted to hold the arms down to keep the screening sheet effective.

5. In a front-strike typewriting machine, the combination with a traveling carriage and a revolute platen therein, of a shaft 75 journaled at the rear of the carriage, a rock arm at each end of the platen fast upon said shaft, a clip upon each arm adapted to hold a screening sheet to conceal the lines written upon a work-sheet, a spring tending to swing 80 said arms upwardly and rearwardly to carry the screening sheet to ineffective position behind the carriage, and holding means adapted to hold the arms in either of two other positions to screen more or less of the work- 85 sheet.

6. In a front-strike typewriting machine, the combination with a traveling carriage and a revolute platen therein, of a pair of clips, one at each end of the platen, a flexible 90 screening sheet adapted to fall backwardly from said clips to conceal lines written upon a work-sheet passed around the platen, and means for supporting said clips in a plurality of positions to screen more or less 95 of the written work-sheet and also to carry the screening sheet clear of the work-sheet.

7. In a front-strike typewriting machine, the combination with a traveling carriage and a revolute platen therein, of a rock 100 shaft journaled at the rear of the carriage, a rock arm at each end of the platen fast upon said shaft, a clip upon each arm adapted to detachably hold the edges of a screening sheet to enable it to conceal the 105 lines written upon a work-sheet, a spring tending to swing said arms upwardly and rearwardly to carry the screening sheet behind the carriage, a catch adapted to hold the arms down to keep the screening sheet 110 effective, and a stop for arresting the arms at either limit of their throw.

8. In a front-strike typewriting machine, the combination with a traveling carriage, of a bail journaled in said carriage, adapted 115 to hold a screening sheet, a spring normally turning said bail to carry the screening sheet out of the way of the typist, a lug for holding said screening sheet in one position, a finger-piece for releasing said lug, a second 120 lug for holding said screening sheet in another position, and a second finger-piece for operating said second lug.

9. In a front-strike typewriting machine, the combination with a traveling carriage 125 and a rotatable platen therein, of a frame including a paper-table and having ends in which said platen is journaled, brackets adapted to be fastened upon said ends, a rock shaft journaled in said brackets behind 130

said table, a flexible screening sheet adapted to be attached to said rock shaft to be swung behind the table, and a device including a releasing finger-piece for holding said sheet in effective position.

10. In a front-strike typewriting machine, the combination with a traveling carriage and a rock shaft adapted to be detachably mounted therein, of rock arms comprising 10 clips fast upon said shaft, a flexible screening sheet detachably held in said clips to bend back over a work-sheet, a spring normally tending to carry said screening sheet out of the way of the typist to fall down at 15 the back of the carriage, and a device for locking it in effective screening position.

11. In a front-strike typewriting machine, the combination with a traveling carriage and a rock shaft adapted to be detachably 20 mounted therein, of rock arms comprising clips fast upon said shaft, a flexible screening sheet detachably held in said clips to bend back over a work-sheet, a spring nor-

mally tending to carry said screening sheet out of the way of the typist to fall down at 25 the back of the carriage, and means for locking it in either of two effective screening positions.

12. In a front-strike typewriting machine, the combination with a traveling carriage 30 comprising a paper-table, of a rock arm near each end of the carriage, a rock shaft behind said table to which said arms are fast, a turned-up spring upon each rock arm adapted to detachably hold a screening sheet to 35 cover a written work-sheet remaining in said carriage, and bearings adapted to be detachably fastened on the carriage and upon which said rock shaft is journaled to permit the screening sheet to be swung to ineffective 40 position behind the table.
